UNITED STATES PATENT OFFICE

146,537

DESIGN FOR A RADIO CABINET

Jack De Young, Grand Haven, Mich., assignor to
Zenith Radio Corporation, a corporation of
Illinois
Application December 8, 1945, Serial No. 124,513

Term of patent 3½ years

(Cl. D56—4)

To all whom it may concern:

Be it known that I, Jack De Young, a citizen of the United States, residing at Grand Haven, in the county of Ottawa and State of Michigan, have invented a new, original, and ornamental Design for a Radio Cabinet, in which the following is a specification, reference being had to the accompanying drawing, forming a part thereof, wherein a single figure shown on the accompanying sheet of drawings is a front perspective view of a radio cabinet, showing my new design.

The characteristic features of my design reside in the front panel section of the cabinet. The ends of the cabinet are the same and the rear panel is plain and unornamented.

I claim:

The ornamental design for a radio cabinet, as shown and described.

JACK DE YOUNG.
